UNITED STATES PATENT OFFICE.

CARL A. RUECKER, OF ST. PAUL, MINNESOTA, ASSIGNOR, BY DIRECT AND MESNE ASSIGNMENTS, TO HERMANN WEIGT, OF ST. PAUL, MINNESOTA; ANNA BERTHA EMILIE WEIGT ADMINISTRATRIX OF SAID HERMANN WEIGT, DECEASED.

SAW-FILING MACHINE.

1,045,442.

Specification of Letters Patent. Patented Nov. 26, 1912.

Application filed March 22, 1909. Serial No. 485,042.

To all whom it may concern:

Be it known that I, CARL A. RUECKER, a citizen of the United States, residing at St. Paul, in the county of Ramsey and State 5 of Minnesota, have invented certain new and useful Improvements in Saw-Filing Machines, of which the following is a specification.

My invention relates to improvements in saw filing machines, its object being to provide a machine by which saws may be quickly and accurately filed, which has, among other things, means for adjustment to teeth of different pitch, and means for 15 setting and adjusting the saws.

More particularly my invention consists in the features of construction, combination and arrangement of parts hereinafter particularly described and claimed.

In the accompanying drawings forming part of this specification, Figure 1 is a perspective view of the machine; Fig. 2 is a perspective view of part of the mechanism employed for supporting a circular saw in the machine; Fig. 3 is a detail of a pin used in connection with the machine for supporting a circular saw; Fig. 4 is a view on line $y-y$ of Fig. 1; Fig. 5 is a similar section partly broken away and showing the parts in different position and also showing some of the parts in outline which in Fig. 4 are shown in section; Figs. 6 and 7 are detail views of a cam forming part of my machine; Fig. 8 is a perspective view of a locking device for the frame; Fig. 9 is a perspective view of the lower end of the file support; Fig. 10 is a plan view of the supporting block for the lower end of the file; Fig. 11 is a view on line $x-x$ of Fig. 10; Fig. 12 is a front view of part of the mechanism for carrying the saw through the machine; Fig. 13 is an end view of Fig. 12; Fig. 14 is a section on line $z-z$ of Fig. 12; Fig. 15 is a top view of Fig. 12; Fig. 16 is a side view of an adjusting arm forming part of the invention, partly broken away; Fig. 17 is a view of the arm taken at right angles to Fig. 16, and Fig. 18 is a side elevation of the handle and adjacent 0 parts.

In the drawings A represents the frame of the machine, upon which a bed plate 2 is slidably supported as by means of dovetailed connection 3. A saw 4 is removably held at the outer edge of the bed plate as 55 by means of a pair of jaws 5 and 6, the jaw 5 being preferably secured upon the outer edge of the plate and the jaw 6 having thumb screw support 7 in the arms 8, said arms having pivotal connection 9 with 60 the bed plate. A pair of diamond shaped stops 10 are pivotally supported in front of the forward edge of the bed plate to engage with the teeth at the opposite ends of the saw 4 and hold the saw edge in alinement 65 with the edge of the bed plate.

Forming a support for the filing mechanism and for the mechanism for imparting longitudinal movement to the plate 2 is a frame B. The frame B has pivotal support 11 on the sides of the machine base and is adapted to be set in adjusted positions upon said support by means of a thumb screw 12 passing through the bottom of the frame and engaging with the guide-way 13 carried by the machine base. 70 75

In order to impart longitudinal step by step movement to the bed plate I provide the following mechanism. Journaled upon the frame B is a transverse operating shaft 80 14 carrying at one end a cam 15. Having fulcrum support 16 upon the side of the frame B alongside said cam is an arm 17, an antifriction roller 18 having slidable support 19 in the upper end of said arm in 85 position to be engaged by the periphery of the cam 15. A scale 20 is carried by the upper end of the arm 17 in connection with the antifriction roller 18 for the purpose hereinafter set forth. The lower end of the 90 arm 17 has pivotal connection 21 with a head 22 having screw shaft connection 23 with a block 24 slidably supported upon the inner side of the frame B as by means of the dovetailed joint 25. The block 24 carries a pair of hinged fingers 26 held rearwardly against the teeth of the saw by means of springs 27. The rotation of the shaft 14 will cause the outer curved edge 95 of the cam to turn the arm 17 upon the 100

fulcrum 16, sliding the block 24 forward and carrying with it the saw by means of the engagement of the fingers 26 therewith. As the roller 18 reaches the cutaway portion 28 of the cam 15 the arm 16 will by gravity swing back to normal position. By means of the thumb screw 19 the throw of the arm is adjusted to adapt the machine to saws having teeth of different pitch, and by means of the thumb screw 23 the block 24 is adjusted to bring the fingers 26 properly into alignment with the teeth.

In order to file the saw teeth the file 29 is supported in bearings 30 slideable in the vertical bar 31 having hinge support 32 at its lower end upon the cross bar 33 of the frame B. In Fig. 10 is shown a method of fastening the file in the bearings which consists of a clamp 34 formed with an opening 35 to receive the end of the file and with a screw 36 threaded through the side of the bearing head and engaging with said clamp. By adjustment of the screw 36 the size of the opening 35 may be restricted. The blocks 30 are provided with runways 37 slideably engaging with the vertical bar 31. The upper end of the bar 31 is formed with an opening 38 through which the shaft 14 passes, the bar 31 adjacent to said shaft carrying an antifriction roller 39 engaging with the front face of the cam. Secured to the lower block 30 is an upwardly extending spring arm 40 formed at its upper end with a relatively large opening 41 through which the shaft 14 passes. A coil spring 42 is interposed between the arm 40 and bar 31 to force the bar inwardly into the cutaway portion 43 of the cam when the parts are in the position indicated in Fig. 4.

44 indicates an operating handle secured upon the shaft 14 and carrying an inwardly extending roller 45 projecting into the opening 41.

In operation the saw 4 is first secured between the jaws 5 and 6 as indicated in Fig. 1, and the arms set by means of the thumb screws 19 to accord with the pitch of the teeth of the saw to be filed the adjustment being determined by the scale 20. The handle 44 then being actuated will by means of the engagement of the roller 45 with the wall of the opening 41, lift the arm 40, as indicated in Fig. 18, and with it the file. The rotation of the shaft 14 by the handle 55 will cause the cam 15 to force the upper end of the bar 31 outward against the tension of the spring 32 when the roller 39 is being engaged by the outer portion of the face of the cam. When the cutaway portion 49 of the face of the cam is being carried past the antifriction roller 39 the spring 42 will force the upper end of the arm 31 inward as shown in Fig. 4 carrying and holding the file in engagement with the teeth of the saw.

Consequently during that portion of the time that the bar is forced inward by its spring the file will be engaging with and acting upon the teeth of the saw and during the remainder of the time the cam will be holding the upper end of the bar 31 outward and the file out of engagement with the saw. The cam is so positioned that the file will be held in contact with the teeth during either the upward or downward stroke, and out of contact with the teeth of the saw during the opposite stroke. The rotation of the shaft 14 by the handle 44 will likewise impart step by step movement to the block 24 to carry the saw forward the distance of one tooth for each forward movement. As the saw is being carried forwardly through the machine the abutments 10 will be turned upon their pivotal supports to prevent their impeding the movement of the saw. Where it is desired to use the device in connection with a circular saw I may use the pin 46 detachably fitted in the opening 47 in the bed plate and rotatably supporting the circular saw 48.

I claim as my invention:

1. A machine of the class described comprising in combination a fixed base, a longitudinally slideable saw support on said base, a frame pivotally supported on said base to swing in a vertical plane, means carried by said frame and coöperating with said base to hold said frame in adjusted positions, a file support vertically slideable in said frame, and means for swinging said frame upon its pivotal support and imparting step by step movement to said slideable saw support. 90

2. A machine of the class described comprising in combination a fixed base, a longitudinally slideable saw support on said base, a frame pivotally supported on said base to swing in a vertical plane, a vertically slideable file support, a guide frame for said file support pivotally supported at its lower end upon said frame to swing in a plane at right angles with the plane of movement of said frame, an operating shaft, and means actuated from said operating shaft for reciprocating the upper end of said guide frame and for imparting step by step movement to said slideable saw support. 105

3. A machine of the class described comprising in combination a fixed base, a longitudinally slideable saw support on said base, a frame pivotally supported on said base to swing in a vertical plane, means carried by said frame and coöperating with said base to hold said frame in swung positions, a vertically slideable file support, a guide frame for said file support pivotally supported at its lower end upon said pivoted frame to swing in a plane at right angles with the plane of movement of said first mentioned frame, spring means normally holding the 115

upper end of said guide frame pressed inward, an operating shaft supported by said frames, and means actuated from said operating shaft for reciprocating the upper 5 end of said guide frame against the tension of said spring and for imparting step by step movement to said slidable saw support.

In testimony whereof I affix my signature in presence of two witnesses.

CARL A. RUECKER.
